UNITED STATES PATENT OFFICE.

HEINRICH KARL, OF JERSEY CITY, NEW JERSEY.

METHOD OF TREATING TRAFFIC RAILS.

No Drawing. Original application filed July 19, 1923, Serial No. 652,531. Divided and this application filed October 28, 1925. Serial No. 65,480.

The use of crushed coke or of metal filings that can be mixed with a little water, or of a compound of crushed coke and metal filings, is necessary on railroads on which signalling or automatic control of the trains is made through the transmission of the electric impulses sent through traffic rails, which impulses have to be picked up by some contact part of the train such as, for instance, some of the train wheels.

It is apparent that when sand is employed as the means for preventing the train wheels from sliding on the rails, there is an imperfect electric contact between the traffic rails and the train wheels if not a complete insulation, since sand even in crushed condition can be ranged among those materials that have electricity insulating properties.

In order, therefore, to prevent interference in the transmission of the electric impulses sent through traffic rails and some parts of the train that contact with them, it is necessary to use an electricity conducting material for sanding the rails, that is, a material that substitutes the sand, and which has no insulating properties. A ma-

terial of that kind would be the filings of certain metals such as copper, iron, brass, etc., but as the use of metal filings would be too costly for that purpose, I propose the use of crushed coke that represents an electricity conducting material whose electricity conducting property nearly equals that of said metals.

I am aware that there are still other materials that might be used for the purpose set forth in this specification, which, however, may not be of such practicability as those mentioned, but in all events I claim all those materials that may be fairly embodied in the spirit and scope of my invention.

What I claim is:

In a method for treating traffic rails that serve also as electric conductors, crushed coke deposited on top of the traffic rails for preventing the train wheels from sliding and permitting the transmission of the electric impulses from the train to the trackside or vice versa, as set forth.

HEINRICH KARL.
